DESIGN FOR A WRAP

Adolph Brieff, New York, N. Y.

Application April 21, 1936, Serial No. 62,230

Term of patent 3½ years

To all whom it may concern:

Be it known that I, Adolph Brieff, a citizen of the United States of America, residing in Manhattan, county of New York, and State of New York, have invented a new, original, and ornamental Design for a Wrap, of which the following is a specification, reference being had to the accompanying drawing, forming part thereof, wherein,

I claim:

The ornamental design for a wrap, substantially as shown.

ADOLPH BRIEFF.
